(57) **CLAIM**

The ornamental design for a frame for a wheeled, manually moveable air compressor, as shown and described.

DESCRIPTION

FIG. 1 is an elevated perspective view of a presently preferred embodiment of the frame for a wheeled, manually moveable air compressor;

FIG. 2 is a plan view of the right side of a presently preferred embodiment of the frame for a wheeled, manually moveable air compressor, the left side plan view being a mirror image thereof;

FIG. 3 is a plan view of the left side of a presently preferred embodiment of the frame for a wheeled, manually moveable air compressor, the right side plan view being a mirror image thereof;

FIG. 4 is a front view of a presently preferred embodiment of the frame for a wheeled, manually moveable air compressor; FIG. 5 is a rear view of a presently preferred embodiment of the frame for a wheeled, manually moveable air compressor; FIG. 6 is a top view of a presently preferred embodiment of the frame for a wheeled, manually moveable air compressor; FIG. 7 is a bottom view of a presently preferred embodiment of the frame for a wheeled, manually moveable air compressor; and,

FIG. 8 is an elevated perspective view of the embodiment of FIGS. 1-7, but from the opposite side of the view shown in FIG. 1.
